UNITED STATES PATENT OFFICE

2,621,436

TOY FIREARM

John H. Weimer and Harry J. Rockey, Sr., Lancaster, Pa., assignors to The Hubley Manufacturing Company, Lancaster, Pa., a corporation of Pennsylvania

Application March 2, 1951, Serial No. 213,614

2 Claims. (Cl. 42—57)

1

This invention relates to toys and is more particularly concerned with toy firearms.

The general object of this invention is the provision of a toy firearm such as a toy rifle or pistol in which explosive caps are fired.

A specific object of this invention is the provision of a toy firearm of the type mentioned in which the magazine and the feeding and detonating mechanism are all combined in a single removably detonating unit.

Another object is to provide such a toy which is safe in use and presents no danger to a child or other person, especially when being fired.

Further objects include the provision of a toy of the type mentioned which is easily loaded, positive in action, sturdy in construction and which in appearance resembles real firearms of any of the various types.

These and other objects and advantages of the invention will appear more fully from the following description in conjunction with the accompanying drawing, in which:

Figure 1 is a side elevational view of an embodiment of the invention in the form of a toy rifle.

Figure 1a is a fragmentary perspective view showing the manner in which the barrel member and forestock are connected to the intermediate section.

Figure 2 is an enlarged side elevational view of the intermediate section of the embodiment containing the removable unit, the removable unit itself being shown in the open or dropped position.

Figure 3 is a perspective view of the removable unit with the magazine gate open.

Figure 4 is an inside perspective view of one half of the intermediate section in which the removable unit is disposed.

As previously indicated, the present invention is applicable to toy firearms in general, such as rifles or pistols, but a distinctive feature resides in the provision of a completely self-contained detonating unit which carries all of the necessary operating mechanism and lends itself particularly to an embodiment in a toy firearm of the type of a rifle consisting of barrel and stock portions which may be taken apart more or less after the fashion of real weapons of this type. In addition to facilitating manufacture in the respect that all of the operative parts of the toy are provided in one unit which may be readily assembled with the body of the gun, the construction and arrangement of parts is such that the safety and ease of manipulation from the standpoint of

2

juvenile operation is such that the value of the device from the standpoint of a toy is materially enhanced.

Referring with more particularity to the drawing in which like numerals designate like parts, the embodiment illustrated comprises a toy rifle having a barrel 11, a fore-stock 12, a stock 13, and an intermediate section 14. The stock and fore-stock are preferably of a plastic material but any other suitable material may be used, such as wood.

The barrel 11 is disposed in a socket 14 at the front end of the intermediate section and is secured in position by a bolt 15 passing through it. Below the socket 14, a stub 16 projects from the intermediate section and engages a socket 17 of the fore-stock 12. The fore-stock is secured in position by means of screws or bolts 18 and 19 passing upwardly through the fore-stock and in threaded engagement with the barrel.

The stock 13 is attached to the rear end of the intermediate section by means of lobes 20 extending rearwardly on either side of the intermediate section. Inwardly extending fins 22 on the inside of the lobes 20 engage slots (not shown) of the stock to prevent pivotal movement between the stock and the intermediate section. A bolt 24 passes through the lobes and the stock to hold them together securely.

The intermediate section itself is fabricated of complementary longitudinal hollow parts 25 and 26 held together by means of bolts 27, 28, 29 and 30 each of which slidably passes through a boss in one of the section parts such as the boss 31 and is threaded engaged with an aligned boss on the other section part.

The said intermediate section contains a compartment open at the bottom to slidably receive the detonating unit 32 containing the magazine, firing mechanism and feeding mechanism. Said combination unit comprises a substantially rectangular member containing the usual cap reel receiving pin or post 33, anvil 34, hammer 35, tape feeding mechanism 36, trigger 37 and trigger guard 38, these parts being constructed and assembled with the usual auxiliary parts well known in the art.

One side of the unit 32 is provided with a pivoted gate 39 which is opened when a reel or tape of caps is to be loaded on the post 33 and then closed. Said gate is provided with a lip 40 at the bottom to facilitate opening it.

Downward movement of the unit is limited by abutment pins 41 extending outwardly from the sidewalls of the unit and which are adapted to

engage the flanged edges 42 at the bottom wall of the compartment.

The unit is held in an upward position by means of a latch comprising a horizontal latch bolt 43, slidably mounted on a pair of longitudinally spaced brackets 44 and 45 having a downwardly projecting arm 46, slidably disposed in a slot 47. A coil spring 48 is mounted in compression between the forward bracket 44 and the arm 46, substantially as shown, to urge the bolt 43 rearward. In this position the rear end of the bolt engages the front end of the unit immediately above which there is placed or formed on the unit an upwardly tapering wedge or lug 49, the bottom of which abuts the bolt and prevents the unit from dropping down until the arm 43, which is provided with a knob 50 on the outside, is moved forwardly against the action of the spring a distance sufficient to move the bolt out of the vertical path of the lug 49. In its closed or upward position, the unit is spring loaded by means of a spring 51 which has a loop 52 disposed about an inner boss 53, and a pair of fingers, one of which abuts the top of the compartment and the other of which rests on top of the unit in a groove formed by two parallel projections 54 or by any other suitable means. It may be seen, therefore, that the unit is constantly urged to its open position by the spring 51 but it is retained in the closed position by means of the latch mechanism hereinabove described. Accordingly, the unit is automatically opened by releasing the latch engagement.

Although this invention has been described with respect to a particular type of toy rifle, it is apparent that it can also be used for other types of toy rifles, as well as for guns, pistols and other firearms.

We claim:

1. In a toy firearm, a hollow section having a bottom opening, a detonating unit slidably mounted in said opening, said unit being nor-

mally disposed in said hollow section, said unit containing means for holding a tape of explosive caps, an anvil and hammer for detonating said caps, means for feeding said tape between said anvil and hammer, resilient means for urging said unit downwardly relative to said opening, and latch means for holding said unit in said hollow section against the action of said resilient means.

2. A toy rifle comprising a barrel, a fore-stock, a stock and a hollow intermediate section, means for securing said barrel and fore-stock to each other and to one end of said section, means for securing said stock to the other end of said section, said section having an opening in the bottom thereof, a unit slidably mounted in said opening, said unit being normally disposed in said hollow section and containing means for holding a tape of explosive caps, an anvil and hammer for detonating said caps, means for feeding said tape between said anvil and hammer, resilient means for urging said unit downwardly relative to said opening, and latch means for holding said unit in said hollow section against the action of said resilient means.
